US0D1109501S

(12) **United States Design Patent** (10) Patent No.: **US D1,109,501 S**
(45) Date of Patent: ** Jan. 20, 2026

(54) **FOOTWEAR ARTICLE**

(71) Applicant: **Amer Sports Canada Inc.**, North Vancouver (CA)

(72) Inventors: **Christopher S. Pope**, Portland, OR (US); **Karen Lee**, Portland, OR (US)

(73) Assignee: **Amer Sports Canada Inc.**, North Vancouver (CA)

(**) Term: **15 Years**

(21) Appl. No.: **29/959,734**

(22) Filed: **Aug. 27, 2024**

(51) LOC (15) Cl. **02-04**

(52) U.S. Cl.

USPC **D2/907**; D2/902; D2/969; D2/972

(58) **Field of Classification Search**

USPC D2/897, 902, 905, 906, 907, 908, 916, D2/918, 925, 943, 946-962, 969, 972, D2/977

CLAIM

The ornamental design for a footwear article, as shown and described.

DESCRIPTION

FIG. 1 is a front, side perspective view of a footwear article; FIG. 2 is a front view thereof;

FIG. 3 is a rear view thereof;

FIG. 4 is a first side view thereof;

FIG. 5 is a second side view thereof; and,

FIG. 6 is a top view thereof.

The broken lines depict portions of the footwear article that form no part of the claimed design.

1 Claim, 5 Drawing Sheets
